UNITED STATES PATENT OFFICE.

PHILIP A. BECKER, OF NEW YORK, N. Y.

DISPLAY-LID.

1,180,632.

Specification of Letters Patent. Patented Apr. 25, 1916.

Application filed December 19, 1913. Serial No. 807,685.

To all whom it may concern:

Be it known that I, PHILIP A. BECKER, a citizen of the United States, and a resident of New York, borough of Brooklyn, 5 county of Kings, and State of New York, have invented a certain new and useful Improvement in Display-Lids, of which the following is a full, clear, and exact specification.

10 This invention relates to a class of devices adapted to be used in conjunction with boxes.

My invention has for its object primarily to provide a display lid designed to be applied to a box in a manner so that it may be hingedly swung to open or closed positions upon the open top of the body of the box whereby merchandise contained therein may be displayed for sale without being subjected to the contaminating influence of the air, or the collection of dust, and wherein is provided a plate of glass, or other transparent material framed in wire of corresponding thickness, thereby obviating the use of the customary forms of metal frames employed for this purpose and which invariably cover so much of the marginal edge portions of the plate that the goods in the box are prevented from being properly exhibited.

Other objects of the invention are to provide a number of clamps adapted to serve as means for securing the frame against displacement to the plate; to provide means whereby the transparent plate and its frame may be detachably pivoted to the body of the box; to provide a holder for permitting the lid to be removably held to the lid of the box, as occasion requires, so that the display lid may be swung to open, or closed positions upon the body of the box by moving the lid of the box accordingly; and to provide upon the holder means serving to permit a number of interchangeable signs to be displayed thereon.

A further object of the invention is to provide a display lid of simple and efficient construction, and which is susceptible of being made in various sizes so as to be used in conjunction with boxes of different sizes.

A practical embodiment of the invention is represented in the accompanying drawing forming a part of this specification in which similar characters of reference indicate corresponding parts in all the views, the said invention being more fully described herein-

after and then pointed out in the claims at the end of the description.

In the drawing, Figure 1 is a perspective view of one form of display lid embodying my invention, showing its use when applied to a box. Fig. 2 is an end view, partly broken away, of the display lid and box shown in Fig. 1. Fig. 3 is a top plan, partly broken away, of the transparent plate and its frame. Fig. 4 is a top plan, partly broken away, of a slightly different form of the display lid. Fig. 5 is an end view of the plate shown in Fig. 4. Fig. 6 is an enlarged plan view of one of the clamps used for securing the frame to the transparent plate, and Fig. 7 is an enlarged view of the formation of the clamp when applied to the transparent plate and its frame.

The display lid has a plate 10 of glass, or other transparent material which may be substantially rectangular, or of other suitable shape so as to be movably applied upon the open top of the body 11 of a box 12 having a lid 13 hinged to its rear wall. The transparent plate 10 is mounted in a frame 14 having a front bar 15, a rear bar 16, and two side bars 17 and 18. All of the bars 15, 16, 17, 18 are made preferably of metal wire of a gage corresponding to the thickness of the plate, though any other suitable material to provide similar bars may be used, and these bars are formed so as to be positioned against the edges of the transparent plate, as shown in Fig. 3, without overlapping the marginal edge portions of the plate, as is incident to frames of this type ordinarily in use.

Serving as means to hold the frame 14 against accidental displacement to the transparent plate 10, I provide a plurality of clamps, as 20. The clamps 20 are alike in formation, and each of said clamps has two spaced heads or disks, as 21 and 22. The heads 21 and 22 of each of the clamps are preferably substantially circular in shape, and each pair of the heads are connected by a narrow integral neck, or shank 23. When the frames are made in limited sizes one of the clamps is employed upon each corner thereof, but when the frame is made of large sizes additional clamps may be used intermediate its corners. In applying the clamps 20 to hold the transparent plate and its frame together, the shank of each clamp is bent so that the heads 21 and 22 thereof are in spaced opposed relation, and the

clamp is then disposed in overlapping arrangement upon the frame for one of the heads of the clamp to engage the underside of the frame and contiguous part of the transparent plate and the second head to engage the top surfaces of the frame and adjacent part of the transparent plate. The clamps may then be soldered, or otherwise rigidly held to the frame. When a transparent plate provided with this form of frame is employed in conjunction with the body of a box the merchandise contained therein will be practically unobstructed for being displayed to the best advantages, thereby obviating the use of the customary forms of metal frames employed for this purpose, and which invariably cover so much of the marginal edge portions of the plate that the goods in the boxes are prevented from being properly exhibited.

As illustrated in Figs. 4 and 5, forms of the frame 14 may be made wherein the rear bar 16 is dispensed with, and instead the side bars 17 and 18 are provided so as to be of sufficient lengths whereby their free ends will extend some distance beyond the rear edge of the transparent plate, and the extensions of these bars are angularly bent, as at 19 and 19^a, so that the free end portions thereof are disposed toward each other and are spaced from the rear edge of the transparent plate. Also adapted to be used in conjunction with the transparent plate and this form of the frame 14 is a strip of metal, or other suitable material, as 19^b. The strip 19^b is disposed at an angle relatively to the transparent plate and its frame, and is adapted to be positioned transversely of the lower part of the lid of the box when the display lid is in use. On the lower longitudinal edge of the strip 19^b is provided an angularly projecting flange 19^c which is applied under the rear edge portion of the transparent plate, and the flange is soldered or otherwise secured to the underside of the side bars 17 and 18 of the frame. When this form of display lid is applied to a box it is positioned so that the side edges of the lid of the box will be guided between the angular extensions 19 and 19^a and the strip 19^b. By then directing the display lid so that the transparent plate and its frame will rest upon the top of the body of the box, the strip 19^b will be disposed across the lower part of the box lid which on being moved accordingly will swing the transparent plate and frame to open or close positions on the open top of the body of the box. Also for the purpose of permitting the lid to be removably held to the lid of the box as occasion requires so that the display lid may be swung to open, or closed positions upon the body of the box by accordingly moving the lid of the box, a holder, as 26, is provided.

65 The holder 26 has a supporting strip 27

which extends upwardly at an angle with relation to the transparent plate 10, and said strip is adapted to be disposed transversely of the lower part of the lid of the box. When the holder is used in conjunction with the forms of the frame, shown in Figs. 1 and 2, upon the lower longitudinal edge of the strip may be provided a substantially L-shaped flange 28 which extends at a right angle relatively to the strip so that the upwardly projecting arm of the flange will be spaced from the strip to provide the holder with a lower longitudinal groove 29. To fasten the holder 26 to the transparent plate and its frame, the holder is arranged so that the L-shaped flange 28 will be disposed upon the upper surface of the rear edge portion of the plate and frame, and upon the ends of the second arm of the flange is provided two laterally extending fingers, as 30 and 31, which are bent over the frame and under the transparent plate. By then soldering the fingers to the frame the holder will be held securely to the transparent plate. Extending from the upper longitudinal edge of the strip 27 is a second flange 32 which is approximately the shape of an inverted L, and this flange is also disposed at a right angle relatively to the strip so that its downwardly projecting arm will be opposed to the upwardly projecting arm of the flange 28 as well as being spaced from the strip to provide the holder with an upper longitudinal groove 33. The flanges 28 and 32 serve as means to permit a number of plates 34 having various signs, as 35, inscribed thereon to be removably mounted in the grooves 29 and 33 of the flanges, whereby the signs may be interchangeable for advertising different brands of goods. On the ends of the strip 27 are provided two vertically disposed sleeves 36 and 37 which are preferably formed by making the strip of sufficient length to provide laterally disposed extensions which are bent in approximately L-shapes so that the end portions thereof are spaced from the strip. To apply the holder 26 and the transparent plate and its frame to a box having a lid hinged thereto, these parts are directed so that the side edges of the lid of the box will be received in the sleeves 36 and 37 of said holder. The holder is then guided to the lower part of the box lid for the transparent plate and its frame to rest upon the open top of the body of the box. The transparent plate and frame may thereby be swung to open, or closed positions on the box by directing the lid of the box back and forth relatively to the body of the box.

In the foregoing description, I have embodied the preferred form of my invention, but I do not wish to be understood as limiting myself thereto, as I am aware that modifications may be made therein without

departing from the principle or sacrificing any of the advantages of this invention, therefore I reserve to myself the right to make such changes as fairly fall within the 5 scope of the appended claims.

Having thus described my invention, I claim as new and desire to secure by Letters Patent:—

1. A display lid supplemental to a box 10 having a lid hinged thereto, adapted to be applied on the open top of the body of the box, comprising a wire frame in which is mounted a transparent plate, said wire frame engaging and in contact with the 15 edges of the plate, and having a cross-sectional diameter such that the opposite planes of the faces of the plate are coincident with planes tangential with the periphery of the frame, and means on the frame, 20 adapted to detachably engage the lid of the box so that the display lid may be swung to open and closed positions on the body of the box when the lid of the box is moved accordingly.
2. In a display lid of the character described, a transparent plate adapted to be movably applied upon the open top of the body of a box, a frame on the transparent plate, said frame being composed of a metal 25 bar disposed around the peripheral edges of the transparent plate so as to lie against the straight edges of the plate, and said bar being of the same thickness as the plate, means securing the bar to the plate, and 30 means provided on the frame for pivotally connecting the frame and the plate to the box, whereby the display lid may be swung to open or closed 35 positions thereon.
3. In a display lid of the character described, a transparent plate adapted to be 40 movably applied upon the open top of the body of a box, a frame on the transparent plate, said frame being composed of a wire bar disposed around the edges of the 45 transparent plate so as to lie against the straight edges of the plate and said wire bar being

of the same thickness as the plate, and clamps securing the bar to the plate.

4. In a display lid of the character described, a transparent plate adapted to be 50 movably applied upon the open top of the body of a box, a frame on the transparent plate, said frame being composed of a section of wire disposed around the edges of the plate so as to lie against the same, and 55 said wire section being of a diameter equal to the thickness of the plate, clamps securing the wire to the plate, and means provided on the frame for pivotally connecting the frame and the plate to the box for movement with the box lid.

5. In a display lid of the character described, a transparent plate adapted to be 60 movably applied upon the open top of the body of a box, a frame on the transparent 65 plate, said frame being composed of a metal bar disposed against the edges of the transparent plate so as to lie against the straight edges of the plate, means securing the bar to the plate, a strip on one edge of the plate, 70 connected to the bar, and means provided on the strip for pivotally connecting the frame and the plate to the box, whereby the display lid may be swung to open or closed 75 positions thereon.

6. In a display lid supplemental to a box having a lid hinged thereto, adapted to be positioned on the open top of the box, comprising a wire on three edges of a substantially rectangular transparent plate, clips 80 securing the frame to the plate, and a strip on the fourth edge of the transparent plate, connected to the wire, and means on the strip for detachably fastening the display lid to the box lid, substantially as set forth 85 and for the purpose specified.

This specification signed and witnessed this eighteenth day of December A. D. 1913.
